UNITED STATES PATENT OFFICE.

JAMES S. CLINTON, OF CHICAGO, ILLINOIS.

CUP-CAKE MACHINE.

1,162,751.

Specification of Letters Patent. Patented Dec. 7, 1915.

Application filed June 13, 1912. Serial No. 703,442.

To all whom it may concern:

Be it known that I, JAMES S. CLINTON, a citizen of the United States, residing at Chicago, in the county of Cook and State of Illinois, have invented a certain new and useful Improvement in Cup-Cake Machines, of which the following is a full, clear, concise, and exact description; reference being had to the accompanying drawings, forming a part of this specification.

10 My invention relates to a machine for manufacturing cup cakes, and has as its principal object to automatically line baking tins with paper and to automatically deposit the proper quantity of dough in the tins after they have been so lined.

15 A second object of my invention is to decrease the labor cost in the preparation of small cakes for baking.

20 A third object of my invention is to increase wholesomeness and promote sanitation of baked articles by decreasing the amount of handling which the article will require.

25 A further object of my invention resides in the particular arrangement and combination of parts hereinafter described.

Referring to the accompanying drawings, Figure 1 is a top plan view of my machine; Fig. 2 is a vertical cross section on the line 2—2 of Fig. 1, looking in the direction of the arrows; Fig. 3 is a side elevation of my machine taken from the left of Fig. 1; Fig. 4 is a detail view partly broken away and parts being shown in section of the mechanism for feeding the dough into the tins and regulating the amount delivered to each tin; Figs. 5 and 6 are detail views of the devices for regulating the dough delivered to each 30 tin and cutting off the dough at the proper point; Fig. 7 is a detail sectional view of the mechanism for cutting paper for the tins and delivering the paper so cut into the tins; Figs. 8 and 9 are detail views of the 35 cutting mechanism shown in Fig. 7, Fig. 8 being a top plan view of the fixed cutter, the remainder of the mechanism being removed, while Fig. 9 is a bottom view of one of the reciprocating cutters, the stamping mechanism having been removed; Fig. 10 is a detail view in elevation of the cam and lever for operating the device shown in Figs. 5 and 6; Figs. 11 and 12 are detail views of the mechanism for giving the table a step 40 by step movement during the cutting and filling operations; Fig. 13 is a plan view of one of the paper blanks made by the cutting mechanism for lining the interior of the cake tins; Fig. 14 is a detail sectional view on line 14—14 of Fig. 2.

60

Referring more particularly to the drawings, 1 is a table which is mounted on a shaft 2 having a step bearing 3. The shaft 2 also has a bearing 4 in a supporting casting or bracket 5. Mounted on the shaft 2 65 intermediate the hub of the table 1 and the bearing 4 is a spider 6 which is connected to the under face of the table 1 by means of bolts 7^a, so that the two rotate together. Power for driving the spider 6 is obtained 70 from the shaft 7 which is driven by a belt wheel 7^b, or any other suitable means. On the inner end of the shaft 7 is a gear 8 which meshes with a gear 9 which is carried by a shaft 10. Shaft 10 is provided with four 75 bearings, one in the block 11, one in the casting 12 and two others in the blocks 13 and 14, respectively. Mounted at one side of the block 13 is a bevel gear 15 which meshes with a gear 16 on a shaft 17. Shaft 80 17 is vertical and is carried in two bearings supported by the casting 12. At the upper end of the shaft 17 is the member 18 which gives to the spider 6 and the table 1 a peculiar step by step movement. One end of 85 the member 18 is in the form of a crank which carries an upwardly projecting pin 19, on which is mounted a revoluble spool or roller 20. The other part of the member 18 is in the form of a semi-circular disk 90 or cam 21 which lies in a lower plane than the roller 20, as clearly shown in Fig. 11. The exterior edge of the spider 6 is provided with two sets of surfaces, one for co-operating with the roller 20 and the other for 95 co-operating with the disk 21. The surfaces which co-operate with the roller 20 are in the form of teeth 22 which lie in the same plane as the roller 20 and are separated by recesses slightly wider than the diameter of the roller 100 20. On a lower plane than the teeth 22 and on the same level with the disk 21, the edge of the spider 6 is provided with a series of cam surfaces 23 shown in plan partly in dotted lines in Fig. 12. These cam surfaces 105 are arcs of circles whose radii correspond to the radius of the exterior edge of the disk 21, the points of intersection between the surfaces 23 being intermediate the teeth 22. Now it will be understood that the shaft 17 110 is rotated continuously by the connections previously described with the shaft 7, but

that while the disk 21 remains in engagement with a particular cam surface 23, the spider 6 and consequently the table 1 is held firmly in stationary position. However, as the disk 21 passes out of engagement with its coöperating cam surface the roller 20 engages one of the teeth 22 giving the spider and table a positive movement in the direction of the arrow.

10 The table 1 is provided with a shoulder 24 which causes the exterior surface of the table to act as a shelf upon which may be placed tins 25 to be used for baking cupcakes. Intermediate two adjacent tins are 15 provided upstanding ridges or webs 26 which are each provided with a lug 27 for holding the tins securely to the table while the machine is in operation.

Carried by a standard such as 28 is a stationary cover plate or apron 29 which covers a little more than half of the surface of the revolving tins, and upon which is mounted the cutting and feeding mechanism herein-after described. It will be understood by 25 those engaged in baking that it is desirable to line the separate recesses or indentations of the tins 25 with separate pieces of oiled paper to prevent the dough from sticking to the tins, while it is being baked and also 30 to protect the baked cakes from dirt and contamination while being handled, these pieces of paper being removed from the tins with the cake after baking. The mechanism for cutting such pieces of paper and placing them in the tins will now be described.

At the outer end of the shaft 10 is a gear wheel 30 which meshes with a gear 31 on the shaft 32. At the end of the shaft 32 opposite from the gear 31 is a crank arm 33 40 which is provided with a slot 34 which provides an adjustable connection with the link or rod 35. The rod 35 is connected at its upper end to a lever 36 which is loosely mounted on the shaft 37. Since the member 45 33 rotates continuously the upper end of the rod 35 and consequently the lever arm 36 is oscillated about the center of shaft 37. The lever arm 36 carries a pawl 38 shown in dotted lines in Fig. 2 which engages with 50 the teeth of a ratchet wheel 39. Consequently as the lever 36 oscillates it gives a step by step movement to the shaft 37 by means of the pawl and ratchet. Mounted on the shaft 37 are two drums or wheels 40 55 and 41 for driving the paper webs 42 and 43 from which the pieces are cut which are placed in the tins. Mounted immediately below the drums 40 and 41 respectively are drums 44 and 45, the web 42 being led 60 around the outer surface of the drum 40 and in between drums 40 and 44 while the web 43 is led around the outer surface of the drum 41 and in between the drums 41 and 45. The upper part of the drum 41 being 65 below the level of the table the web 43 is

guided on to the drum 41 by means of the roller 46. It will be understood moreover that the drums 44 and 45 are suspended below drums 40 and 41 by means of brackets 47—47. The shaft 37 being positively 70 driven, the drums 40 and 41 in connection with 44 and 45 serve to feed the paper webs positively. The webs 42 and 43 are carried by separate rollers 48—48 which are mounted on a shaft 49, carried in brackets 50—50 75 mounted on the upper face of the plate 29. The webs 42 and 43 are also guided by the rolls 51—51. In order to prevent the webs 42 and 43 from feeding too freely I provide 80 friction rollers 52—52 which are carried by a shaft 53 which is pivotally mounted in the brackets 50—50. If desired the shaft 53 may be thrown up into the dotted position shown in Fig. 2 so as to permit the ready removal or replacement of the webs 42—43. 85 The brackets 50 are provided with extensions 54—54 against which the arms 55—55 which support the shaft 53 may rest when the rolls 52 are lifted. After leaving rollers 51 the webs 42 and 43 run horizontally until 90 they reach the drum 40 and the roll 46 respectively. In passing through this horizontal stretch the webs are cut to provide pieces for lining the tins and the cut pieces are placed automatically in the tins. As shown 95 in Figs. 1 and 2 the tins have a radial depth of three cups or recesses. Consequently I provide three cutters 56, 57 and 58. Owing to the fact that the pieces of paper are cut from a flat web and folded into the tins the 100 diameter of the pieces must be greater than that of the top of the tins. Consequently the outer edges of the cutters overlap the outer edges of the recesses in the tins and all three of the cutters can not be placed in 105 a row radially of the table, but one is offset from the other two, as plainly shown in Fig. 1. The detail of the cutter mechanism is shown in Figs 7, 8 and 9, the cutter 57 being 110 selected for detailed illustration. Each cutting mechanism comprises a stationary and a reciprocating part, the stationary part being carried on the upper face of the plate 29 and comprising an upstanding cylindrical knife plate 59 which has a sharp circular 115 knife edge at its top. The fixed knife 59 is held in position by annular plates 60, plates 60 being attached to the face of the plate 29 by screws 61, and each extending approximately 90 degrees arc. Plates 60 form a 120 central aperture through which the pieces of paper 62 shown in Fig. 7 may be placed in the tins after being cut from the web. Attached to the inner face of the knife 59 and held between two adjoining plates 60 are 125 four radial knives 63 placed 90 degrees apart around the plate 59, and extending to the edge of the aperture 64 in the plate 29. Above the knife 59 is a reciprocating knife 65 which is also cylindrical in form but has 130

its cutting edge at the bottom, the knife 65 mating with the knife 59 on the inside. The knife 65 also carries radially placed knives 66, which are mounted between ridges 67—67 on the interior face of the part 68, and are also held in place by two sets of screws as shown in Fig. 7. The radial knives 66 co-operate with the fixed radial knives 63 to produce four radial slits 100 in the papers 62 so that when the paper is forced into the tins the edges of the slits may overlap each other and allow the papers to be forced into the tins without wrinkling. One of the papers 62 having the slits cut therein is shown in Fig. 13.

The part 68 is mounted at the end of a tubular sleeve 69 which slides in a bearing in the bracket 70 and is operated by being attached to a yoke plate 71. Mounted to slide within the sleeve 69 is a rod 72 at the lower end of which is mounted the mechanism for placing the papers 62 in the tins after the papers have been cut from the web. This mechanism consists of a stamping member or head 73 which is attached to a stud or shank 74. The end of the rod 72 is drilled out to receive the shank 74 and the rod 72 is also slotted as at 74^a to receive a pin 75 for retaining the shank within the end of the rod and for allowing a certain relative movement between the two. The shank 74 does not fit closely in its bore, so that head 73 is allowed play in both the vertical and horizontal directions. A spring 76 normally forces the head 73 outwardly so that the pin lies at the lower end of the slot, but when the head comes in contact with the interior of the tins the spring 76 may be compressed, thus avoiding pounding on the tins, but insuring that the paper shall be firmly placed in position.

The cutting mechanism and the stamping mechanism just described are operated from two cam grooves formed in opposite faces 45 of the cam plate 77 which is mounted on the shaft 10 between the blocks 13 and 14. Cam rollers mounted in these grooves operate rods 78 and 79 respectively. One of these rollers 86 is shown in dotted lines in Fig. 3, being hidden by the gear 30 and the member 87. These rollers are mounted on the plates 87 and 88, the supporting nuts being shown in Fig. 2. It will be understood that the plates 87 and 88 are forked and embrace 50 the shaft 10 on each side, so as to avoid the necessity of a fixed bearing and an additional link at the upper end of the rods 78 and 79. The rod 78 connects at its upper end with a pivoted lever 80, as best shown in Fig. 3. This lever 80 is pivoted to a casting 81 which is mounted on top of a bridge shaped casting 82 in which are the bearings 70 for the tubes 69 and rods 72 previously mentioned. At the end of the lever 80 60 opposite the operating rod 78, the lever con-

nects with the shaft 89 which is pivoted in the castings 81 and 81^a, the shaft 89 and the castings mentioned, appearing in plan in Fig. 1. The shaft 89 carries a lever 80^a which is pivoted directly to a lug on the plate 71 for operating the plate. Similarly the rod 79 connects with the lever 83 and the lever in turn with the pivoted shaft 89^a, also pivoted in the castings 81 and 81^a. The shaft 89^a carries a lever 83^a which is connected at its outer end to a short link 84 pivoted in turn with the plate 85, to which are connected the rods 72 for operating the heads 73. It will be understood that the grooves in the cam plate 77 are so cut that the rod 78 will first be operated to cut one of the pieces 62 from the webs and that the rod 79 will next be operated to force the piece down into the tin.

Owing to the fact that the cutting mechanism 56 is in a different radial plane from cutters 57 and 58, it follows that in order to avoid an unnecessary waste of paper the cutter 56 is provided with a separate web of paper from the cutters 57 and 58. This arrangement has been previously described, but it follows from this that the web 43 which co-operates with the single cutter 56 should be fed only half as fast as the web 42 which serves the cutters 57 and 58. This difference in speed of travel between the two webs is provided for by the different diameters of the driving in drums 40 and 41.

Carried on the plate 29, in a different radial position from the cutting and stamping mechanism, is a feeding mechanism for placing a proper amount of dough in each tin. This mechanism comprises a hopper 90 which appears in Figs. 1, 2 and 3, and is shown in detail in Fig. 4. At the bottom of the hopper are mounted three sets of feeding mechanism which are mounted below a plate or member 91 having apertures therein, through which the dough feeds, these apertures being separated by ridges 91^a. The hopper 90 is bolted directly to plate 91 by which it is supported. Immediately below the member 91 is a revoluble member 92 which is formed with gear teeth 93^a on its outer surface. Each of the members 92 is provided with a central aperture, to the inner surface of which is attached a feeding worm or screw 93 so that the worm turns with the member 92. The members 92 are mounted to revolve in bearings 94 supported by a bridge casting 95 which is attached to the upper surface of the plate 29 and which also supports the plate 91 above the members 92 by means of supporting rods 96—96 cast on plate 91. Carried between the upper and lower webs of the casting 95 are fixed tubes 97—97, into which the worms 93 depend. Below the mouths of the tubes 97 is mounted cut-off mechanism especially illustrated in Figs. 5 and 6. This cut-off mecha-

nism comprises a reciprocating plate 98 shown in end view in Fig. 4, and side view in Fig. 5, and in inverted plan view in Fig. 6. This plate 98 is provided with slide plates 99 which are attached to the upper face of the plate 98 along two sides and are spaced along the inner edges from the plate 98 to engage the upper surfaces of guides 100 which depend from the bridge casting 105. The plate 98 is provided with elongated apertures 101—101, through which the dough delivered by the worms 93 may drop into the tins. On the under face of the plate 98 are cutting plates 102—102, which are slotted as shown at 103, so that they may be adjusted on the plate 98 to vary the size of the aperture 101, and consequently the point at which they cut off the dough from a given tin, thus regulating the amount of dough in the tins. Plates 102 are provided with crescent shaped cutting edges 104—104, as shown in Fig. 6.

The feeding mechanism is operated from the shaft 7 by the gear wheel 105 which meshes with a gear 106 which drives a shaft 107 at the upper end of which is a gear 108. The teeth of the gear 108 mesh with the teeth 93^a on the outer surface of one of the members 92, and as the teeth 93^a of all the member 92 mesh with each other, the gear 108 drives them all in unison. The plate 98, however, is operated from the cam 109, also carried on the shaft 7, and shown in detail in Fig. 10. The cam 109 drives a lever 110 which operates a rod 111. Rod 111 connects at its upper end to a lever 112, which connects with a shaft 120 pivoted at the upper end to castings 113^a. Shaft 120 carries two lever arms 112^a which are connected by short links 113, to the plate 98 in order to reciprocate the plate.

In the operation of my device it will be understood that the table 1 carrying the cake tins 25, is given a step by step movement by means of the mechanism heretofore described in which there is a perceptible pause between each forward movement or step of the table. While the table 1 is stationary between the successive steps, the cutting mechanism cuts the pieces 62 from the webs 42 and 43, and the stamping mechanism places the pieces of paper in the tins. As the table is stepped around tins containing papers are brought under the dough feeding mechanism whereupon during one of the stationary periods the plate 98 is operated by the link motion connected thereto to present apertures 101 beneath the tubes 97 whereupon the worms 93 deliver a charge or dough into the tins. Upon the return stroke of the plate 98 the dough is cut off and immediately thereafter the table is moved forward a step and the operation just described is repeated. When a given tin has been completely filled with dough it is removed from

the table 1 and an empty tin inserted in its place without the necessity for stopping the machine.

It will be understood by those skilled in mechanical arts that while I have shown and described the preferred form of my device, that various rearrangements and modifications thereof may be made without departing from the spirit of my invention. For instance instead of a circular revolving table I may use an endless belt or conveyer for carrying the tins, and mount the cutting, stamping and feeding mechanism above such conveyer instead of above the table shown. Consequently it will be understood that I contemplate all modifications and rearrangements which are mechanically equivalent to the device shown and described herein.

Having thus described my invention, what I claim is:

1. The combination of a movable device for carrying baking tins, mechanism for lining said tins with paper, means for placing dough on said paper, and means for moving said device.

2. The combination of a movable device for carrying baking tins, mechanism for lining said tins with paper, means for placing dough on said paper, and means for giving said device a step by step movement.

3. In a machine for preparing cup cakes, a movable table for carrying baking tins, means for moving said table with a step by step motion, means for passing a paper web above said tins, reciprocating cutters for cutting blanks from said web, reciprocating heads for pushing said blanks into said tins, feeding worms mounted above said table for forcing dough into said tins, and a reciprocating plate or cutter for gaging the amount of dough delivered by the worms.

4. In a machine for preparing cup cakes, a movable table for carrying baking tins, means for moving said table with a step by step motion, means for passing a paper web above said tins, reciprocating cutters for cutting blanks from said web, reciprocating heads for pushing said blanks into said tins, means for feeding dough into said tins, and means for gaging the amount of dough delivered by said dough feeding means.

5. In a machine for preparing cup cakes, a movable table for carrying baking tins, means for moving said table with a step by step motion, means for passing a paper web above said tins, reciprocating cutters for cutting blanks from said web, reciprocating heads for pushing said blanks into said tins, and means for feeding dough into said tins.

6. A cup cake machine comprising a rotary carrying table, means for giving the same a step by step motion, means for lining tins placed upon said table comprising cutting devices arranged above said table and

at different distances from the center thereof, and reciprocating heads associated with said cutting devices for placing the paper in the tins, and dough feeding mechanism comprising a hopper mounted above the table and a plurality of feed devices arranged at different distances from the center of the table.

7. A cup cake machine comprising a rotary table, a set of cutting devices mounted above said table at different distances from the center, a series of dough feeding devices also mounted above said table at different distances from the center, and means for 10 rotating said table and for operating said cutting devices and said dough feeding devices.

8. A cup cake machine comprising a rotary table, a set of cutting devices mounted above said table at different distances from the center, a series of dough feeding devices also mounted above said table at different distances from the center, a series of lining heads mounted above the table at different distances from the center thereof, and means 15 for rotating said table and also for operating said cutting devices and said dough feeding devices.

In witness whereof, I hereunto subscribe my name this 6th day of June, A. D. 1912. 20
JAMES S. CLINTON.

Witnesses:

A. L. JONES,
HAZEL JONES.
